UNITED STATES PATENT OFFICE

HERMON L. VAN VALKENBURG, OF WAUWATOSA, WISCONSIN, ASSIGNOR TO SQUARE D COMPANY, OF DETROIT, MICHIGAN

CUT-OUT MECHANISM FOR ELECTRIC SWITCHES

Application filed July 8, 1930. Serial No. 465,460.

This invention relates to cut-out mechanism for electric switches, and is particularly directed to a cut-out mechanism for fluid actuated switches.

- 5 It is the usual practice to provide either pressure or vacuum switches which are fluid actuated and which control an electric motor or other electrical device, which is responsive to the condition of the fluid.
- 10 It is not always desirable to have the electric motor or other electrical device responsive to changes in the condition of the fluid means. In order to accomplish this, it has heretofore been necessary to provide an auxiliary switch in the motor circuit which could be opened whenever it was desired to throw the motor completely out of operation or to render it unresponsive to changes in the fluid condition responsive mechanism. It is
- 15 20 obvious that this construction necessitated additional wiring and involved quite an additional expense in material and labor in addition to requiring wall space.

This invention is designed to overcome the defects noted above, and objects of this invention are to provide cut-out means for an automatic electric switch, such cut-out means cooperating directly with the electric switch and mechanically locking it either in open position or in closed position depending upon the design of the device.

Further objects are to provide a cut-out mechanism which may be carried bodily by the automatic switch, which does not require additional wiring or additional wall space, but which forms a unitary portion of the automatic switch itself.

Further objects of this invention are to provide a cut-out mechanism for an electric switch which is of very simple construction, which may be made with the utmost cheapness, which requires a minimum amount of change in order to adapt an automatic switch to the new use, and which is compact and eminently practical.

Embodiments of the invention are shown in the accompanying drawings, in which:—

Figure 1 is a vertical sectional view through a pressure responsive switch.

50 Figure 2 is a side elevation taken from the

opposite side from that as viewed in Figure 1.

Figure 3 is a sectional view on the line 3—3 of Figure 1.

Figure 4 is a sectional view corresponding to Figure 1 showing a modified form of the invention, the device in this figure being operable by a movable rod such as a float rod.

Figure 5 is a fragmentary view of a further form of the invention showing the construction of switch applicable to vacuum control.

Referring to Figures 1, 2 and 3, it will be seen that the electric switch comprises a housing 1 which may be mounted in any suitable manner upon an appropriate support. This housing is rigidly attached to the casing 2 of a diaphragm 3. If desired, the support for the housing may be obtained solely from this source, although this feature forms no portion of the invention.

The casing is provided with a transverse pin or shaft 4 upon which the main rock lever is pivoted. This rock lever is provided with bell crank arms 6, see Figures 1 and 3, which are pivoted to downwardly projecting lugs 75 carried by the plate 7.

A plurality of studs 8 extend upwardly through the capsule or casing 2 and are attached at their lower ends to a pressure plate 9 which bears against the diaphragm 3. The upper ends of these studs are reduced and fit into apertures in the plate 7, spacers being provided, if desired, between the studs 8 and the plate 7, as indicated in Figure 1.

A main spring 10 bears at its lower end against the plate 7 resisting the motion of the diaphragm, and at its upper end bears against an adjustable washer 11 loosely mounted upon a threaded stem 12 rigid with the casing. An adjusting nut 13 controls the pressure of the spring 10.

The main lever 5 is provided with a pivoted link 14 at its upper end which is urged downwardly by means of an adjustable spring 15. The outer end of the link 14 is provided with a cam roller 16 which travels upon a pointed cam 17 which has oppositely beveled cam faces, as may be seen from Figure 1. The cam 17 forms the upper portion of a rock lever 18 pivotally mounted inter-

mediate its ends to the casing 1. This rock lever is connected in any suitable manner with the switch mechanism proper. For example, by means of a slot and pin connection, it may be operatively joined to a triangular plate 19 which, in turn, is connected by means of a link 20 to the movable portion 21 of the switch, such movable portion being preferably pivoted and carrying the movable contacts 22. Stationary contacts 23 are carried by the switch and cooperate with the movable contacts.

The details of the switch are more fully set forth in my copending application Serial No. 537,250, filed May 14, 1931.

It is to be noted that some active portion of the switch operating mechanism is provided with a projecting member which extends outwardly through the casing. In the form chosen for illustration, the rocking plate or rocking member 19 is provided with a pin 24 which not only pivotally joins the link 20, but also extends outwardly through an arcuate slot 25 formed in the side wall of the casing 1. This pin 24 is most clearly shown in Figure 2 and the arcuate slot 25 through the casing is indicated in dotted lines in such figure.

On the outer side of the casing a cut-out lever 26 is pivotally mounted upon a pin 27. This cut-out lever may be manually operable by means of a handle 28, if desired, or it may be operated by an electromagnet, or in any other obvious manner. In the form chosen for illustration, manual operation has been indicated.

The cut-out lever 26 is provided with a projecting portion extending beyond the pivot point and pivotally carrying a locking link or member 29. This link or locking member 29 is in reality a sheet metal stamping pivoted, as indicated at 30, to the end of the lever 26 and provided with spaced ears 31 and 32 which limit the two extreme positions that this lever may take, as shown in full and dotted lines in Figure 2.

The locking link or member 29 is also provided with an ear 33 which is apertured and which receives one end of the tension spring 34. The other end of the tension spring is passed through an aperture in the pin 27 and serves to lock the lever 26 against outward movement.

The locking member 29 is thus carried solely by the lever 26. This locking member is provided with a slot 35 which accommodates the pin 24. Normally the slot 35 roughly aligns with the slot 25, as may be seen from Figure 2, and permits the pin 24 to rock back and forth in accordance with the motion of the member 19, see Figure 1. Consequently, in the full line position of the parts shown in Figure 2, the switch may open or close in an automatic manner and may ac-

cordingly control the instrumentality, such as the motor, to which it is connected.

However, when it is desired to lock the switch in open position, the lever 26 is rocked downwardly into the dotted line position shown in Figure 2. The slot 35 is now moved into its dotted line position and restrains the pin 24 from moving along the slot 25 and consequently locks the switch in open position.

In view of the fact that the members 29 and 26 are in essence toggle links, it is apparent that it is merely necessary to have the member 29 move slightly past dead center when in its dotted or switch locking position, as viewed in Figure 2. The spring 34 thus holds the member 29 against inadvertent movement. No amount of force exerted by the pin 24 can shift the position of the member 29, as the initial movement of the pin 24 is towards the pivot point 27 and slightly below the pivot point 30 when in dotted line position, as viewed in Figure 2. In other words, the members 29 and 26 are locked slightly past dead center.

In the form of the invention shown in Figure 4, substantially the same idea is followed. However, a traveling rod 36 actuates the switch mechanism. This rod may be a float rod, if desired, or may be some other type of movable rod. It is provided with stops 37 at spaced points which engage a lever 38 pivoted at 39 within the housing 40 of the switch, the rod 36 loosely passing through the eyelet portion 41 of the lever 38. The lever 38 is connected by means of a link to a main rock lever 42 which corresponds to the rock lever 5, see Figure 1, a suitable stop 43 being provided to limit the motion of this rock lever. The rocking member 19', see Figure 4, is operatively connected, in a manner similar to that previously described, to the lever 42 and actuates an electric switch, not shown, by means of the link 43. In the position of the parts shown in Figure 4, the switch will be held closed, as the link 43 is thrust upwardly into its uppermost position, and when the member 19' is rocked to the right, as viewed in Figure 4, the link 43 will be drawn downwardly, thus opening the switch.

A slot 44 is formed in the casing 40 through which the pin 45 of the rocking member 19 may pass in the same manner as previously described.

A cut-out lever 46 is pivoted, as indicated at 47, to an outer wall of the casing and is provided at one end with an operating handle 48 or other operating means. The other end of the lever pivotally carries the locking member 49, similar to the member 29 previously described, and provided with a slot 50 to receive the pin 45. In the position of the parts shown in Figure 4, the switch is locked in closed position. Obviously the mechanism could be so arranged as to lock the switch either open or closed.

Figure 5 is intended to show a construction whereby the switch may be operated by means of a vacuum controlled diaphragm 51. In this form the diaphragm is connected to a 5 headed plunger 52 which operates an intermediate lever 53. This lever is formed of spaced parts, each provided with an outwardly turned bearing finger 54 which fits within the notched portions of downwardly projecting arms 55. The arms 55 are in operative relation to the pressure plate 56 which is pivoted to the rock lever 57, such rock lever corresponding identically to the lever 5, see Figure 1, in function and mode of operation.

10 It will be seen that the invention is applicable to different types of electric switches and that the cut-out mechanism may be operated in any suitable manner.

15 It will be seen, further, that the cut-out mechanism is so associated with the automatic switch that the automatic switch is not only automatically controlled, but also is manually controlled, so that the necessity of an auxiliary manually or otherwise controlled switch 20 is wholly avoided and the automatic switch thus performs a dual function.

25 It will be seen further that the mechanism is very simple, is cheap, and is compact, and may be most readily associated with the 30 switch mechanism to form a unitary structure.

35 Although this invention has been described in considerable detail, it is to be understood that such description is intended as illustrative rather than limiting, as the invention may be variously embodied and is to be interpreted as claimed.

I claim:

1. The combination of an electric switch, 40 fluid actuated means for operating said switch, said switch having a movable member, a snap latch adapted to snap into either of two positions, one position being across the path of movement of said movable member, and the other position being out of the 45 path of movement of said movable member, and means for moving said snap latch into one or the other of said two positions.

2. In an electric switch having a movable 50 member, latching means comprising a control lever, and a latching member pivoted to, and bodily carried by, said control lever, said latching member holding said switch against movement in one position of said control lever by engaging the movable member of said 55 switch.

3. In an electric switch having a movable member, latching means comprising a control lever, and a latching member pivoted to, and 60 bodily carried by, said control lever, said latching member holding said switch against movement in one position of said control lever by engaging the movable member of said switch, said latching member and said lever 65 forming a toggle joint.

4. In an electric switch having a movable member, latching means comprising a control lever, a latching member pivoted to, and bodily carried by said control lever, said latching member holding said switch against 70 movement in one position of said control lever by engaging the movable member of said switch, and a spring having its ends attached to said lever and said latching member.

5. A latching means for an electric switch 75 having a movable member, said latching means comprising a control lever, a latching member bodily carried by and pivoted upon said control lever and having a slot for receiving the movable member of said switch, 80 a pair of ears formed on said latching member to limit its rocking motion relatively to said lever, and a spring having its ends fastened to said latching member and said control lever.

85 6. In a device of the class described, a switch having a movable member, latching means for latching said movable member in one position, said latching means comprising a pivotally mounted lever, a triangular latching member pivoted adjacent an apex to said lever and having ears forming stops located at two of the apices, and a spring secured to said triangular latching member and to said lever, said latching member being carried solely by said lever and having a slot for the reception of said movable member, said latching lever and said latching member constituting toggle levers, and in one position 90 passing dead center with one of said ears bearing against said lever, said slot receiving said movable member in the extreme end of such slot adjacent said lever when said lever is rocked to latching position.

95 In testimony whereof, the signature of the 105 inventor is affixed hereto.

HERMON L. VAN VALKENBURG.
